UNITED STATES PATENT OFFICE.

FRANK HOFFMANN AND CHARLES LAMOUR, OF PHILADELPHIA, PENNSYLVANIA.

SCAFFOLD.

Application filed February 23, 1927. Serial No. 170,091.

Our invention relates to scaffolds such as are used in the construction of tall buildings, and has for its principal object to provide a scaffold frame which may be readily raised 5 or lowered by one man.

Another object of our invention is to provide a scaffold which may be readily adjusted to a horizontal plane while suspended.

Still another object of our invention is to 10 provide a scaffold having means for locking the raising mechanism and means to automatically release the locking device when the scaffold is lowered.

These objects, and other advantageous 15 ends which will be described hereinafter, we attain in the following manner, reference being had to the accompanying drawings in which

Figure 1 is a side elevation of a scaffold 20 frame embodying our invention,

Figure 2 is an end view thereof,

Figure 3 a fragmentary sectional view taken on the line 3—3 on Figure 2, and

Figure 4 a fragmentary view taken on the 25 line 4—4 on Figure 3.

Figure 5 is a top plan view of one end of the channel forming the bottom of the scaffold frame, and

Figure 6 an end view thereof.

30 Referring now more in detail to the drawings, the scaffold frame is composed of a top strut 10 having bifurcated ends supporting hangers 11, one of which carries a hanger bar 12 while the other carries a hanger cable 13 with a channel 14 supported between their 35 lower ends. A drum 15 is mounted on a shaft 16 rotatable in each hanger 11 and carries a cable 17 by means of which the scaffold frame is supported.

40 A scaffold consists of two or more scaffold frames having planks extending from one to the other and resting on channels 14; the distance between the several frames depending on the nature of the work to be performed, 45 the load to be carried by the scaffold, and the strength of the planking used. The frames are suspended with cable 13 toward the building in order that the workmen may have as free access as possible to the work 50 upon which they are engaged.

Top strut 10 is preferably made from two bars having their central portions riveted together and each end bent outwardly, as shown in Figures 1 and 2. Each hanger 11 55 preferably consists of two bars bent to form a substantially U-shaped member; the upper

end of each bar being connected to one of the bars forming top strut 10, preferably by bolts in order that the scaffold frame may be demounted. Cable 13 has one end attached to the lower end of one hanger 11 and its other end secured to one end of channel 14 in any suitable manner, as by means of a casting 18 attached to the under side of channel 14 and provided with an eye 19, extending through a slot 20 in channel 14, to which the end of the cable is secured in a well known manner. One end of casting 18 is provided with rounded corners and extends beyond the end of channel 14 so as to 70 abut the wall should the scaffold swing inwardly, thus protecting the wall from the sharp corners of the channel as well as protecting the raising mechanism of the scaffold from injury. Hanger bar 12 is secured to the bottom of the other hanger 11 and either the hanger or the bar is given a half turn so that the lower end of bar 12 may be secured to an angle 21 riveted to the other end of channel 14. The upper end of cable 75 13 and both ends of hanger bar 12 are preferably bolted in place in order that the scaffold frame may be fully demountable.

80 A hook 22 is secured to hanger bar 12 and is adapted to receive a guard rail, such as a piece of 2 by 4 framing, which extends across two or more scaffold frames. A pin 23 is secured in hanger bar 12 at a point above hook 22 and may be bent in any desired shape so that tools or small equipment 85 may be hung thereon for the convenience of the workmen occupying the scaffold.

One end of shaft 16 extends through a bearing 24 secured to one side of hanger 11 and has a worm wheel 25 rigidly secured 90 thereto. A worm bearing 26 is secured to or formed on bearing 24 and has a worm 27, formed on a worm shaft 28, mounted therein and meshing with worm wheel 25. The distance between the ends of bearing 26 is 95 greater than the length of worm 27 so that it may move axially in the bearing as will be later described. The inner end of worm shaft 28 is flattened in order to be straddled by the bifurcated head of a connecting shaft 100 29 and is connected thereto by a single bolt. The other end of connecting shaft 29 also has a bifurcated head which engages the flattened end of a worm shaft 28^a rotatable in a bearing 26^a in which is mounted a worm 105 27^a. The ends of shafts 28 and 28^a are similarly flattened and both ends of shaft 27 are 110

alike with the exception that the slots in the bifurcated heads are disposed at right angles to one another, forming the effect of a universal joint, in order that the worm shafts will not bind in their bearings when the scaffold frame is not level. The scaffold frame is raised and lowered by means of an endless hand chain 30 which engages a chain wheel 31 secured to shaft 28^a. Worm 27 is provided with an annular groove 32 near its outer end while worm 27^a is provided with a groove 32^a near its inner end. With the exception of the location of groove 32^a and the addition of chain wheel 31, worm 27^a and worm shaft 28^a are similar to worm 27 and worm shaft 28.

A ratchet wheel 33, shown as being formed on one side of worm wheel 25, is engaged by a pawl 34 pivoted on a pin 35 extending from bearing 24. A trip 36, rockably mounted on a pin 37 extending from bearing 24, has one end adapted to engage the under side of a projection 38, formed on the side of pawl 34, while its opposite end is bifurcated and straddles the reduced portion of worm 27 formed by groove 32.

In use, the scaffold frame is swung from the building on cables 17 in the usual manner and may be raised by rotating worms 27 by means of hand chain 30. After it is swung free, channel 14 may be leveled by disconnecting shaft 29 from one of the worm shafts and rotating worm 27^a. The shafts are then reconnected and, by rotating worm wheels 25 in an anti-clockwise direction, the scaffold frame will be raised, pawl 34 riding over the notches in ratchet wheel 33. When the desired height has been reached, a slight reverse movement of chain 30 will cause worms 27 and 27^a to move away from ends 39 and 39^a of bearings 26 and 26^a, thus moving the bifurcated end of trip 36 and releasing pawl 34, which will drop into one of the notches in ratchet wheel 33 and remove the strain from the worms and teeth of the worm wheel as well as prevent drums 15 from turning and allowing the scaffold to work downwardly.

When hand chain 30 is operated to lower the scaffold, the worms will move axially in the worm bearings sufficiently to move the upper ends of trips 36 and thus raise pawls 34 away from ratchet wheels 33; which movement simultaneously transfers the load from the ratchet wheels to the worms and allows the scaffold to be lowered. Should it be desirable to stop the downward movement of the scaffold and to hold same in this position by means of the pawl and ratchet wheel, it is only necessary to rotate the worms slightly in the opposite direction in order that the pawl may engage the ratchet wheel.

In the drawings, worm wheel 25 is shown as spaced a considerable distance from the

side of hanger 11 in order to illustrate the relation of the ratchet wheel, pawl and trip but in practice, worm wheel 25 is disposed as closely as possible to the face of bearing 24 and ratchet wheel 33 is preferably formed on drum 15 instead of on worm wheel 25.

While we have described our invention as taking a particular form, it will be understood that modifications may be made without departing from the spirit thereof, and hence we do not limit ourselves to the precise construction set forth, but consider that we are at liberty to make such changes and alterations as fairly come within the scope of the appended claims.

We claim:—

1. A scaffold including a frame, a drum shaft rotatable in each end of the frame, a drum on each drum shaft, a worm wheel on each drum shaft, a worm shaft rotatable in the frame, worms on the worm shaft meshing with the worm wheels, a chain wheel on the worm shaft for rotating said shaft, and separable hinged joints formed in the worm shaft whereby one worm may be rotated independently of the other; the joints being adapted to bend at right angles to each other in order that swaying of the frame will not cause distortion of the worm shaft. 95

2. A scaffold including a frame, a drum shaft rotatable in each end of the frame, a drum on each drum shaft, a worm wheel on each drum shaft, a ratchet wheel on each drum shaft, a pawl engaging each ratchet wheel, a worm shaft rotatable in the frame, worms on the worm shaft meshing with the worm wheels, a chain wheel on the worm shaft for rotating said shaft, and means for automatically disengaging the pawls from the ratchet wheels; said disengaging means being actuated by rotating the chain wheel to lower the scaffold. 105

3. A scaffold including a top strut having bifurcated ends, a bifurcated hanger attached to each end of the strut, a hanger bar carried by one hanger, a hanger cable carried by the other hanger, a platform support secured to the bar and the cable, a drum rotatable in the bifurcated end of each hanger, cables for supporting the scaffold windable on the drums and having their free ends secured to an overhead support, and drum operating mechanism mounted on the hangers, substantially as described. 110

4. In a scaffold raised and lowered by means of a cable wound on a drum secured to a shaft having a worm wheel and a ratchet wheel thereon; a pawl engaging the ratchet wheel; a pair of worm bearings secured to the scaffold; a worm shaft rotatable in the bearings; a worm secured to the shaft and rotatable in the bearings, the worm being shorter than the distance between the ends of the bearings; a trip engaged by the 125

worm and adapted to engage the pawl whereby rotation of the worm shaft will cause the worm to move axially and cause the trip to disengage the pawl from the 5 ratchet wheel.

5. A swinging scaffold including a frame, a drum shaft rotatable in each end of the frame, a drum on each drum shaft, cables windable on the drums and adapted 10 to be secured to an overhead support for suspending the scaffold, a worm wheel on each drum shaft, a worm shaft rotatable in the frame, bendable joints in the worm shaft,

worms on the worm shaft meshing with the worm wheels, a chain wheel on the worm 15 shaft for rotating said shaft, means for locking the drums against rotation in one direction, and means for automatically releasing the locking means; said releasing means being actuated by rotating the chain wheel to lower the scaffold.

In testimony whereof we have signed our names to this specification.

CHARLES LAMOUR.
FRANK HOFFMANN.
